MANUFACTURE OF HALO-FLUORO DERIVATIVE OF ALIPHATIC HYDROCARBONS

Thomas Midgley, Jr., Worthington, Albert L. Henne, Columbus, and Robert Reed McNary, Dayton, Ohio, assignors, by mesne assignments, to General Motors Corporation, a corporation of Delaware

Application February 24, 1931, Serial No. 517,854

5 Claims. (Cl. 260—162)

This invention relates to processes for the manufacture of halo-fluoro derivatives of aliphatic hydrocarbons, and more specifically derivatives such as fluoro-chloro derivatives of methane.

5 It has previously been proposed to manufacture halo-fluoro derivatives of aliphatic hydrocarbons by fluorination of an halogenated aliphatic hydrocarbon. In such a method, all the halogen atoms, other than fluorine, which are desired in the final product are already present in the molecule before fluorination.

10 Our present invention differs from the former methods in that its objects are to fluorate an aliphatic hydrocarbon derivative in which all the halogen atoms desired in the final product are not present before fluorination, and to add the missing halogen atoms, during or after fluorination.

15 As a specific example, CCl_2F_2 , can be obtained, according to our present invention by fluorinating dichloromethane, CH_2Cl_2 to difluoromethane, CH_2F_2 and by subsequently or at the same time chlorinating the CH_2F_2 to dichlorodifluoromethane CCl_2F_2 . The latter operation may be modified to form CHClF_2 or a mixture of CCl_2F_2 and 20CHClF_2 . A partial fluorination of CH_2Cl_2 to CH_2ClF could be subsequently or simultaneously chlorinated to CHCl_2F and/or CCl_3F .

25 In carrying out this invention, an apparatus similar to that diagrammatically shown on the drawing may be used.

30 A fluorating substance, such as antimony trifluoride, SbF_3 , together with a catalytic agent, such as antimony pentachloride, SbCl_5 , are introduced into the autoclave 20 through the opening 21. After the autoclave 20 is closed, a hydrocarbon derivative, such as dichloromethane, CH_2Cl_2 , which, for convenience, is stored in the tank 22, is introduced into the autoclave 20 by means of the pump 23. The reaction then proceeds and may, if 35 desired, be promoted by warming the autoclave 20 with a steam jacket 24. One method of obtaining a good yield of CH_2F_2 is to maintain the pressure at about 130 pounds gauge and the temperature at about 80° F. The CH_2F_2 is then admitted into chamber 26 where it is chlorinated by chlorine fed through conduit 28. The chlorination in the reaction chamber 26 is promoted by the iron filings 27. The amounts of chlorine and difluoromethane entering the reaction chamber 26

40 may be proportionally regulated by means of the valves 29 and 35 respectively. The reaction product CCl_2F_2 is led through the conduit 30 into the washer 31 containing a solution of sodium hydroxide indicated at 32, where HCl and any excess chlorine are removed. Thereafter the dichloro- 45

5 difluoromethane may be compressed into and stored in the container 33 by means of the pump 34.

The above method of manufacture, and the steps involved therein are set forth in the following equation:

10 The above specific example has been set forth to illustrate the production of CCl_2F_2 . However it is possible to also produce a less fluorated substance in chamber 20, for example monochloromonofluoromethane by varying the pressure temperature conditions within this apparatus. In the reaction chamber 26 this monochloromonofluoromethane will be halogenated by the chlorine to produce dichloromonofluoro or trichloromonofluoromethane according to the amount of chlorine introduced. The reactions involving the production and chlorination of monofluoro compound are as follows:

15 In the above description, the halogenation takes place after the fluorination. It is possible, however, to vary the process to carry out both the fluorination and the halogenation simultaneously. For example, the chlorine may be fed directly into the autoclave 20 and the reaction chamber 26 eliminated. In this manner both the fluorination and chlorination will be carried out in the autoclave 20. Or, if desired, both processes may be combined. That is, chlorine may be fed into both the reaction chamber 26 and into the autoclave 20 so as to start the chlorination 20 during fluorination within the autoclave 20 and to bring it to completion in the chamber 26.

25 Derivatives of methane have been used for illustrative purposes but it is likewise possible to fluorinate and subsequently or at the same time halogenate derivatives of the methane homologs. Such fluoro compounds include CHClF_2 , CCl_2F_2 , $\text{C}_2\text{Cl}_2\text{F}_4$ illustrative of the ethane series and $\text{C}_3\text{H}_5\text{F}_2\text{Br}_3$ illustrative of the propane series.

30 In the specific examples, SbF_3 has been named as the fluorating agent and SbCl_5 as the catalytic agent, other fluorating agents such as lead fluoride and zinc fluoride may be used in place of antimony trifluoride and other catalytic agents such as Br_3 , titanium tetrachloride may be used

in place of $SbCl_5$ when an antimony salt is present.

What is claimed is as follows:

1. The process comprising simultaneously reacting an aliphatic hydrocarbon derivative containing hydrogen and halogen other than fluorine with a fluorating agent and with chlorine, the amount of fluorinating agent being insufficient to cause fluorine substitution on all of the carbon bonds, substituting one or more fluorine atoms for the halogen atoms other than fluorine and simultaneously therewith substituting one or more chlorine atoms for one or more hydrogen atoms to thereby obtain a halo-fluoro derivative of an aliphatic hydrocarbon.
2. The process which comprises simultaneously reacting the derivative of methane containing hydrogen atoms and halogen atoms other than fluorine with a metal fluoride and with chlorine, the amount of fluorating agent being insufficient to cause fluorine substitution on all of the carbon bonds, substituting one or more fluorine atoms for one or more of the halogen atoms other than fluorine and substituting simultaneously one or more chlorine atoms for one or more of the hydrogen atoms substantially as described to thereby form a halo-fluoro derivative of methane.
3. The process which comprises simultaneously reacting a derivative of methane containing

hydrogen atoms and halogen atoms other than fluorine with a fluorating agent and with chlorine, the amount of fluorating agent being insufficient to cause fluorine substitution on all of the carbon bonds, substituting one or more fluorine atoms for the halogen atoms other than fluorine and simultaneously therewith substituting one or more chlorine atoms for one or more hydrogen atoms to thereby form a halo-fluoro derivative of methane.

4. The process of manufacturing a halo-fluoro derivative of an aliphatic hydrocarbon which comprises simultaneously interacting a partially halogenated aliphatic hydrocarbon derivative with a metal fluoride and with chlorine, the amount of fluorating agent being insufficient to cause fluorine substitution on all of the carbon bonds, to obtain a halo-fluoro derivative of hydrocarbon.

5. The process comprising simultaneously interacting a partially halogenated aliphatic hydrocarbon derivative with a fluorating agent and with chlorine, the amount of fluorating agent being insufficient to cause fluorine substitution on all of the carbon bonds, to obtain a halo-fluoro derivative.
